Primary Examiner — Melanie Pellegrini*(74) Attorney, Agent, or Firm* — Taft Stettinius & Hollister LLP(57) **CLAIM**

The ornamental design for a pendant, as shown and described.

DESCRIPTION

FIG. 1 is a front elevational view a pendant showing my new design;

FIG. 2 is a back elevational view thereof;

FIG. 3 is a right side elevational view thereof;

FIG. 4 is a left side elevational view thereof;

FIG. 5 is a bottom plan view thereof;

FIG. 6 is a top plan view thereof;

FIG. 7 is a right, front perspective view thereof; and,

FIG. 8 is a left, back perspective view thereof.

The broken lines represent portions of the pendant which form no part of the claimed design.
